(57) **CLAIM**

The ornamental design for an in-car bluetooth MP3 player, as shown and described.

DESCRIPTION

FIG. 1 is a Front elevational view of an in-car bluetooth MP3 player showing new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof; and,

FIG. 7 is a Perspective view thereof.
